INVENTOR

BY Victor J. Evans & Co.

ATTORNEY

UNITED STATES PATENT OFFICE

POSEY D. REYNOLDS, OF RUSTBURG, VIRGINIA

PISTON TOOL

Application filed July 6, 1932. Serial No. 621,108.

This invention relates to tools for pistons and has for the primary object, the provision of a device of the above stated character whereby a piston may be readily handled during the fitting thereof to a cylinder and is so constructed that it will permit the passing of the piston entirely through the cylinder when desired and which may be easily and quickly applied and removed from the piston by gripping the wrist pin of the latter.

With this and other objects in view, this invention consists in certain novel features of construction, combination and arrangement of parts to be hereinafter more fully described and claimed.

For a complete understanding of my invention, reference is to be had to the following description and accompanying drawing, 20 in which

Figure 1 is a vertical sectional view illustrating a tool applied to a piston and constructed in accordance with my invention.

Figure 2 is a side elevation partly in section showing the tool opened and removed from a piston.

Figure 3 is a sectional view taken on the line 3—3 of Figure 2.

Referring in detail to the drawing, the numeral 1 indicates a tool especially adapted for handling pistons and includes a pair of shanks 2 of considerable length. The shanks at one end have formed thereon handles 3 which extend at right-angles to the shanks and may be formed by bending a portion of the shanks. The shanks 2 adjacent the handles are provided with aligned openings 4 to loosely receive a rivet 5 whereby the shanks are pivotally connected. The free ends of the shanks are arcuately curved to form jaws 6 adapted to fit about a wrist pin 7 of a piston 8 as shown in Figure 1. A collar or ring 9 is slidably mounted on the shanks 2 and when moved towards the jaws will urge the latter about a wrist pin to prevent accidental displacement of the tool from the piston. The shanks 2 are preferably of rectangular shape in cross section as shown in Figure 3. To apply the tool 1 to a wrist pin of a piston, the handles are moved to-

ward each other pivoting the shanks so as to open the jaws whence the latter may pass freely about the wrist pin. The collar 9 is then slid in the direction of the jaws closing the latter about the wrist pin. The tool applied to the piston in the aforescribed manner permits a person to fit a piston in the cylinder and due to the lengths of the shanks or the distance which the handles are positioned from the piston, the latter may be moved entirely through a cylinder when desired.

While I have shown and described the preferred embodiment of my invention, it will be understood that minor changes in construction, combination and arrangement of parts may be made without departing from the spirit and scope of my invention, as claimed.

Having thus described my invention, what I claim is:

A tool comprising elongated shanks, arcuate shaped jaws formed on one of the ends of the shanks, handles formed on the other ends of the shanks, said shanks having aligned openings adjacent the handles, a rivet loosely fitted in the apertures to pivotally connect the shanks, and a collar slidable on the shanks to be moved towards the jaws for urging the latter about the wrist pin of a piston.

In testimony whereof I affix my signature.
POSEY D. REYNOLDS.
